Primary Examiner — Nathan M Johnston(74) *Attorney, Agent, or Firm* — Wood Herron & Evans LLP(57) **CLAIM**

The ornamental design for a tissue dispenser, as shown and described.

DESCRIPTION

FIG. 1 is a front perspective view of a tissue dispenser showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken line showing of portions of the tissue dispenser in the drawings is for the purpose of illustrating unclaimed portions of the design and forms no part of the claimed design.

1 Claim, 7 Drawing Sheets(56)
